UNITED STATES PATENT OFFICE.

ARTHUR L. HALEY, OF LOS ANGELES, CALIFORNIA, ASSIGNOR TO A. L. HALEY ARCHITECT INCORPORATED, OF LOS ANGELES, CALIFORNIA, A CORPORATION OF CALIFORNIA.

WALL-SEAT WALL-BED.

982,669.

Specification of Letters Patent. Patented Jan. 24, 1911.

Application filed October 12, 1908. Serial No. 457,431.

To all whom it may concern:

Be it known that I, ARTHUR L. HALEY, a citizen of the United States, residing at Los Angeles, in the county of Los Angeles and State of California, have invented a new and useful Improvement in Wall-Seat Wall-Beds, of which the following is a specification.

This invention relates to that class of beds which is concealed in the wall when out of use and which provides a seat along the wall, the seat being in use when the bed is out of use.

The present invention is an improvement upon the invention set forth in my co-pending application filed June 29, 1908, Serial No. 441,021, for wall-seat wall-bed, and consists of the novel features herein shown, described and claimed.

An object of this invention is to provide a wall-bed, the frame of which is provided on its bottom with a facing and is so mounted by means of a geared rocker and rocker tracks, that when the bed is upright in stored position, it will be held by gravity entirely within the recess except that the facing on the bottom of the bed is in front of, though practically flush with the face of the wall and portions of the rockers and their supports will be in front of the plane of the upright facing, and concealed by a seat-structure that will fold as the bed is lowered.

An object is to so construct the bed and its rockers and plain tracks that in the operation of lowering the bed into position for use, the bed and its frame will be practically balanced upon its rocker at all angles and the bed frame will be moved out of the recess so that the head of the lowered bed will be flush with the face of the wall and in the same position as that occupied by the bottom facing of the bed when the bed is erect.

An object is to prevent any irregular or uneven action in the operation of raising and lowering the bed and to provide for superior ease of simultaneously raising the bed and shifting it back at a simple single movement in one direction and to lower it by a simple single movement in the reverse direction. In order to carry out the invention in this respect the tracks are aslant downward rearwardly at a comparatively small angle with the horizon and project

considerably in front of the wall, and the rockers are considerably wider than the bed frame and project downward therefrom when the bed is down to form legs that fulcrum the bed a considerable distance from the end of the bed frame; and to conceal the rockers and their tracks a seat with a folding support is arranged between buttresses and a special arrangement of parts is provided whereby the seat and its supporting elements assist in holding the bed in its upright position.

One of the principles of this invention is that the bed is carried by a quadrant-rocker that rocks on an inclined track, and is so mounted that when the bed is upright the point at which the rocker rests on the track is always close to and slightly above the center of gravity of the bed.

The accompanying drawings illustrate the invention.

Figure 1 is a front elevation showing a wall-seat wall-bed in its upright or closed position and showing the seat in position for use, the bed being arranged to fold endwise. Fig. 2 is a horizontal section on line a^2 , Fig. 1. Fig. 3 is a vertical section on line a^3 , Figs. 1 and 2. Fig. 4 is a view analogous to Fig. 3 and showing the bed in its horizontal position ready for use with the seat folded out of use. Fig. 5 is a fragmentary cross-sectional detail on line a^5 , Fig. 4. Fig. 6 is a front elevation of a bed arranged to fold sidewise and showing the bed in its horizontal position ready for use. Fig. 7 is a vertical cross-section on line a^7 , Fig. 6. Dotted lines show the folded position. Fig. 8 is an enlarged fragment of the geared rocker-mechanism. Fig. 9 is a cross-section on line a^9 , Fig. 8.

The bed operates in an opening in the wall, said opening being surrounded by the casing or jamb comprising the vertical portions 1 and 2 and the head 3. This casing may be constructed in constructing the building, exactly as a door-casing is constructed. Of course the dimensions must correspond to the dimensions of the proposed bed, and in one case as in Fig. 1 the casing will be constructed to receive the bed endwise, and in the other case as in Fig. 6 the casing will be constructed to receive the bed sidewise.

Rigid arms 4 and 5 extend forwardly from the vertical casings 1 and 2 and may be

of suitable desirable construction. Rocker-bases 6 are inserted against the inner faces of the arms 4 and 5, said rocker-bases being inclined downwardly from the front. 5 The geared rocker-tracks 7 are mounted upon the bases 6. Flanges 8 extend upwardly at one side of each track, and gear-teeth 9 extend upwardly from the flanges, thereby producing geared rocker-racks inclined downwardly from the front, the parts 10 7, 8 and 9 being integral.

The front facing 10 may be of any suitable design large enough to cover the opening 11 in the casing so that the rear of the 15 facing will butt against the front face of the casing preferably all the way around. Light-fixtures 12 may project forwardly from the upper part of the facing 10 to serve as legs for the bed when in its horizontal position. Pedestals 13 project upwardly or backwardly from the rear face of the facing 10, and the bed-frame 14 is supported upon these pedestals.

The geared rockers 15 are bolted to the 25 bed-frame 14 and secured to the edges of the facing 10 and match with the geared rocker-racks upon the bases 6, there being segmental flanges 16 to travel upon the track 7 and engage against the flanges 8, and there being 30 teeth 17 to mesh with the teeth 9. The geared rocker-mechanism is constructed right and left handed so as to hold the bed from lateral movement.

The headboard 18 extends upwardly from 35 the bed-frame 14, there being braces 19 to strengthen the headboard, and the rear facing 20 is hinged to the headboard. Arms 21 project backwardly from near the upper end of the rear face 20 and connecting-rods 40 or links 22 connect the rear ends of the arms 21 to the rear faces of the casing-jambs 1 and 2 so that when the bed is rocked forwardly to its horizontal position the facing 20 will assume the position shown in Fig. 4 and close the opening 11 above the bed.

A box 23 for weights is secured to the bed-frame below and back of the headboard 18. The seat-board 24 is secured to the flange-board 25 and this flange-board is connected 50 by the hinge 26 to the lower edge of the facing 10, so that the seat will swing between the arms 4 and 5, and suitable upholstering 27 is applied to the upper face of the seat-board.

55 A mop-board 28 is secured to the forward ends of the bases 6; hinges 29 are secured to the upper edges of the mop-board; a cleat 30 is secured to the lower face of the seat-board 24 near its transverse center; and 60 hinges 31 are connected to the forward edge of this cleat. The folding-seat-pedestal comprising the vertical board 32 and the flange-board 33, is secured to the hinges 29 and 31 so that when the bed folds forwardly 65 to its horizontal position the seat will re-

tain the horizontal position and fold downwardly and forwardly as shown in Fig. 4. The hinge 31 is considerably back of the vertical plane of the hinge 29 by reason of the flange-board 33 extending backwardly 70 from the upper edge of the vertical board 32, and the hinge 31 is near the transverse center of the seat-board 24 so that when the seat is occupied the weight of the occupants is back of the mop-board 28 and hinges 29, 75 thereby tending to press the bed backwardly and hold it in its upright position against the casing.

If the hinge 31 were in the same vertical plane with the hinge 29 or in front of the 80 hinge 29, pressure upon the seat would tend to tip the seat forwardly and throw the bed forwardly upon the occupants of the seat; whereas, by moving the hinge 31 backwardly to the middle of the seat and back of the support of the pedestal the pressure is reversed and exerted to hold the bed firmly in its upright position.

I desire to call especial attention to the 90 location and construction of the geared rockers. I find that by using comparatively large rockers and inclining the tracks downwardly from the front, I can balance the bed with a great deal less weight than I 95 could otherwise; and assuming that the relation between the weight-box 23 and the bed is properly adjusted and the bed in a horizontal position as in Fig. 4, as soon as the forward end of the bed is elevated the 100 action of the weight will cause the rockers to run down the incline very easily and cause the bed to assume its upright position, and the weights are located below and back of the geared rocker-mechanism as shown in 105 Fig. 3, thereby overbalancing the bed and holding the facing 10 firmly against the casing or jambs.

When the bed is operated from its vertical position it travels forwardly until the head-board 18 is flush with the front face of the jambs, as shown in Fig. 4, thereby bringing the bed entirely out of the opening.

When the casing is properly constructed in preparing the building for the bed it becomes a very simple matter to install the bed. 115 The bases 6 are secured in position by nails or glue or in any suitable way, the bed-structure placed upon the bases in its horizontal position with the rear facing 20 in 120 position to close the opening 11, and then the bearing-blocks 34 connected to the ends of the links 22 are secured to the rear faces of the jambs 1 and 2 and the device is ready for use.

The forward ends of the geared rocker-tracks are as far from the floor as the bed-frame is from the track, as shown in Fig. 4. There is a great advantage in attaching the geared rocker directly to the bed-frame and 125 extending it to the end of the bed-frame,

thereby enabling me to use larger rockers, so that when the bed is operated to a vertical position the weights are near the floor, and when the bed is operated to a horizontal position the bed moves out into the room and is of the desired height. If smaller rockers were used at the extreme ends of the bed-frame it would be necessary to place the geared rocker-tracks farther from the floor and this would raise the bed when in its elevated position or else the bed would not be of the desired height when in its horizontal position. By placing the weight-mechanism directly upon the end of the facing back of the headboard and arranging the rockers so that their rear ends are close to the counterbalance, I am able to get the bed close to the floor and the fulcrum close to the weights when the bed is in vertical position, and then as the bed is tipped forwardly to a horizontal position the fulcrum shifts rapidly away from the weights and also away from the floor so as to correspondingly increase the force of the weights and balance the bed; and the weighted end of the bed is raised bodily; all of which tends to reduce the amount of counterbalance weight required.

The weight-box 23 may be supplied with separate weights not shown in the usual way, that may be increased or decreased in number as required to counterbalance different weights of bedding.

There is a great advantage in placing the seat-pedestal back from the forward edge of the seat-board, as it improves the appearance of the seat and gets the pedestal back under the seat away from the heels of the occupants of the seat.

In the construction shown in Figs. 6 and 7 the headboard becomes a sideboard, the bed being folded sidewise instead of endwise. In other respects there is very little difference in the construction except that the opening into the wall is of different dimensions, and these differences are obvious.

By making the rocker-tracks on an incline from the front downwardly, the rockers travel uphill two or three inches in moving the bed from a vertical position to a horizontal position, and this raises the bed-frame to the standard bed-height, and while the fulcrum is traveling forwardly it is also traveling upwardly so that when it is desired to raise the bed from a horizontal position the rocker is rolling down hill and works easy and requires less weight. At the same time the reverse operation lowers the seat to the standard seat height, whereas, if the rockers traveled on a level the seat would be too high.

The entire device is within the limits of the opening formed by the jambs, and it does not matter what the width of either jamb is or how close it may be to a wall.

The purpose of the gears and flanges is to prevent displacement of the rockers and to hold the bed in true position. I do not limit the device to the use of gears on the rockers as an equivalent for the gears may be employed without departing from the principle of the invention.

The rockers are preferably made in the form of quadrants, one edge of each quadrant being fastened rigidly by bolts 35, 36 to the bed-spring frame 14 and the other edge being rigidly fastened by screws 37, 38 to the front facing 10 of the bed, thus holding the parts firmly together.

I claim:—

1. Geared rocker-bases inclined downwardly from the front, geared rocker-tracks upon the bases, geared rockers upon the tracks, a bed-frame secured to the geared rockers, a front-facing secured to the bed-frame, a seat hinged to the front-facing, and a seat-pedestal hinged to the geared rocker-bases and to the seat, the hinge of the seat being back of the hinge of the bases. 80

2. Geared rocker bases inclined downwardly from the front, geared rocker tracks upon the bases, geared rockers upon the tracks, a bed-frame secured to the geared rockers, there being flanges upon the geared rocker tracks engaging the flanges upon the geared rockers to hold the bed-frame in line; a front facing secured to the bed-frame, a seat hinged to the lower edge of the front facing, and a seat-pedestal hinged to the geared rocker bases and to the seat. 90

3. Geared rocker bases inclined downwardly from the front, geared rocker tracks upon the bases, geared rockers upon the tracks, a bed-frame secured to the geared rockers, a front facing secured to the bed-frame, a seat hinged to the lower edge of the front facing, a seat-pedestal hinged to a rigid support and to the seat, the hinges of the seat being back of the hinges of the support. 100

4. The combination with a bed frame of a geared rocker at one end thereof, a base, a rearwardly and downwardly inclined geared track for the rocker fixed to the base, a seat above the rocker, a hinge above the seat hinging the seat to the bed frame, a hinge underneath and secured to the under side of the seat in front of the rocker, a hinge secured to the base in front of the track, 115 and a folding seat pedestal having a rearward top extension and hinged at its bottom to the base hinge and at its top rear extension to the lower seat hinge, the seat being normal to the bed frame and the pedestal normal to the seat when the bed is erect. 120

5. A casing forming an opening, geared rocker-tracks mounted in the opening and inclined downwardly from the front, geared rockers upon the tracks, a bed-frame carried 130 by the geared rockers, a front facing carried

by the bed-frame, and counterbalancing weights carried by the bed-frame so that the bed will swing to a vertical position with the front facing closing the opening in the 5 casing, a rear facing connected to the head of the bed, and connections between the rear facing and the casing so that when the bed swings to a horizontal position the rear facing will close the opening in the casing, 10 thereby moving the bed forwardly out of the opening.

6. A wall bed comprising a casing, a downwardly and rearwardly inclined geared track extending across the casing from the rear of 15 the casing and projecting in front thereof, the incline of the track being slight, a bed frame accommodated in the casing and provided with a facing to close the opening therein when the bed frame is upright, and 20 geared rockers on the track and fixed to the bed frame and flush with the top of the frame and projecting from the bottom of the frame substantially as and for the purpose set forth.

25 7. The combination with a floor, of a wall provided with a recess, bases on the floor at the sides of the recess, said bases extending into the recess and projecting in front of the wall, buttresses in the angles between the 30 floor and the wall outside the bases and extending above and in front of the bases, geared rocker tracks on the tops of the bases and extending aslant in front of the wall, a bed-frame adapted to fit within the recess 35 and provided on its bottom with a facing to close the upper portion of the opening in

the recess, geared rockers fixed to the bed-frame and projecting from the bottom thereof, beyond said facing and resting upon the geared tracks, and foldable means connected 40 with the frame and with the bases and arranged between the buttresses to conceal the rockers and bases and adapted to form a seat when the bed is erect.

8. In a wall bed construction, a counter- 45 balanced bed frame, geared rocker segments secured to said frame, rocker bases, geared rocker tracks upon said bases, a seat hinged to the front of the bed frame, and a seat support hinged to the geared rocker bases and 50 to the seat.

9. A bed-frame mounted to swing from a vertical to a horizontal position and vice versa, a seat hinged to the bed-frame, and a seat pedestal connected to a hinge rigidly at 55 its lower end and hinged to the seat, said upper hinge being back of the lower hinge.

10. Geared rocker bases inclined downwardly from the front, geared rocker tracks upon the bases, geared rockers upon the 60 tracks, a bed-frame secured to the geared rockers, a front facing secured to the bed-frame, a seat pedestal hinged to a rigid support and to the seat, the hinges of the seat being back of the hinges of the support. 65

In testimony whereof, I have hereunto set my hand at Los Angeles, California, this 5th day of October, 1908.

ARTHUR L. HALEY.

In presence of—
JAMES R. TOWNSEND,
JULIA TOWNSEND.
